Primary Examiner — Dana K Weiland*Assistant Examiner* — Emily Anna Saunders(74) *Attorney, Agent, or Firm* — Jeenam Park(57) **CLAIM**

The ornamental design for a toy crane, as shown and described.

DESCRIPTION

FIG. 1 is a perspective view of a toy crane showing my new design;

FIG. 2 is a front elevational view thereof;

FIG. 3 is a top plan view thereof;

FIG. 4 is a right side elevational view thereof;

FIG. 5 is a rear elevational view thereof;

FIG. 6 is a left side elevational view thereof; and,

FIG. 7 is a bottom view thereof.

The broken lines in the drawings depict portions of the toy crane that form no part of the claimed design.

1 Claim, 7 Drawing Sheets(56)
